Patented Mar. 2, 1909.

UNITED STATES PATENT OFFICE.

RALPH R. ROOT, OF GLENVILLE, OHIO.

HEAT-REGULATOR.

No. 913,982.

Specification of Letters Patent.

Patented March 2, 1909.

Application filed May 6, 1903. Serial No. 155,889.

To all whom it may concern:

Be it known that I, RALPH R. Root, a citizen of the United States, residing at Glenville, in the county of Cuyahoga and State of Ohio, have invented a new and useful Improvement in Heat-Regulators, of which the following is a specification.

This invention relates to heat regulators of that general class that controls the temperature by opening or closing a damper, and it has particular reference to the damper and the mechanism for controlling and turning the same, the object of the invention being the provision of a device of this character that will fully open or close the damper upon a very slight change of the temperature from normal. This object I attain in the structure shown in the accompanying drawings, in which—

20 Figure 1 is a side elevation of my invention with one of the supporting posts omitted, said invention being shown as applied to an incubator, a part only of which is shown in section; Fig. 2 is a front elevation of the regulator; Fig. 3 is a sectional view of the capsule of the regulator and parts of the supporting structure, said view being taken substantially on line 3—3 of Fig. 1; Fig. 4 is a detailed view partly in section of the damper 25 and the escapement mechanism; and Fig. 5 is a view, partly in section and partly in elevation of a baby incubator that is provided with my invention.

Referring now to the drawings, in which 35 similar reference characters designate corresponding parts throughout the several views,

1 represents the upper wall of an incubator, which may be of any suitable type or for any purpose, that shown in Fig. 5 being for babies. In this figure, 2 is a heating tube that passes through the lower portion of the incubator to warm the air therein, said tube terminating at each end outside the incubator, and being turned downwardly and flared 45 into a bell-shape at one of the ends. In this end a lamp or other suitable burner 3, is kept burning for heating the tube. For admitting fresh air, a tube or pipe 4 is provided, said pipe surrounding the tube 2 and extending 50 inwardly to a point about midway between the ends of the incubator, the inner end being preferably beveled, as shown. To hold the tube and pipe apart a proper distance, I interpose spider frames 5 near the ends of the latter. The air entering the incubator is thus conducted along the hot tube 2, and is

partially warmed so that the baby will not be unduly chilled. To further protect it from this fresh air, I provide a hood 6 which covers the inner end of the pipe and deflects 60 the air to the sides of the incubator.

The temperature in the incubator is controlled by the damper 7, which is pivoted to turn in a suitable housing 8, said housing closely fitting the damper so as to be entirely closed thereby when the latter is in a horizontal position. The housing rests upon the outer and upper side of the incubator, and surrounds an opening 9 in said side, the opening being preferably at the center of the 70 incubator. The vanes of the damper are carried by a shaft or arbor 10 that is preferably pointed at the ends and journaled in sockets in the ends of adjusting screws 11 and 12. This forms a very sensitive bearing 75 and is the form I prefer to use, although any other suitable form may be employed if desired. The screw 11 is carried by one side of the housing, but the screw 12 is supported in the upper end of a bent arm 13 that preferably projects from and is secured to the housing, although the arm may be supported independently of the housing. Lock-nuts 14 are employed to secure the screws in their adjusted positions. The damper is turned 80 by means of a weight 15 and cord 16, which cord is wound upon the arbor 10 and passes from thence over a sheave 17 that is journaled in brackets 18, said brackets being secured to the top of the incubator and projecting so as to cause the cord and weight to hang freely over the end thereof. 90

As above stated, when the damper is in a horizontal position, the opening through the housing is completely closed. When the 95 damper is turned into a vertical plane, however, the said opening is substantially unobstructed, the thickness of the vanes and arbor representing but a small portion of the width thereof. To hold the damper in these 100 two positions, I secure to the arbor between the housing and the arm 13 an escapement wheel 19, said wheel having two engaging surfaces or teeth 20. With these teeth are adapted to engage the pallets 21 and 22 of 105 an escapement 23, said escapement being mounted upon an arbor 24 that is journaled in the housing and in an adjusting screw 25 that is carried by the bent arm 13. When the pallet 21 engages with a tooth 20 the 110 damper is closed; but when this pallet is moved so as to permit the weight and cord to

turn the arbor 10, the same tooth 20 moves around until it is engaged with the pallet 22, which will hold the escapement with the damper in its open position. To secure the 5 result of moving the damper one quarter revolution for every movement of the escapement 23, the teeth 20 are diametrically opposite each other and the distance between the pallets 21, 22 is equal to half the distance 10 between the opposite teeth 20 of the escapement wheel 19.

The escapement is operated by means of a lever 26 that is pivoted in brackets 27 on the upper side of the incubator, said lever having 15 a forward bifurcated end that engages with a bent finger 28 on the escapement mechanism. The lever should be as long as practicable, as the sensitiveness of the device increases with the length thereof, and the forward end 20 should be so much heavier than the rear end that when its weight is thrown upon the finger 28 the escapement will be rocked.

The lever 28 is moved by means of a rod 29 that engages therewith at a point just in 25 front of the fulcrum, and the unbalanced weight of the lever is normally supported thereby. The lower end of the rod is supported by a thermostat, said thermostat being preferably a capsule 30. The lower end 30 of the rod is supported by the upper plate of this capsule 30, see Fig. 3, the lower plate of which is supported by a yoke 31, which yoke is suspended from a plate 32 on top of the incubator by posts 33. The brackets 27 in 35 which the lever 26 is fulcrumed, rise from and form a part of the plate 32.

Within the capsule 30, which is supported within the incubator in the region where the heat must be regulated, I place a small 40 quantity of an easily volatilized liquid, as ether. When the heat rises above the normal, the liquid volatilizes within the capsule and bulges the plates apart which lifts the lever 26 and causes the pallet 21 to release the escapement so that the damper 45 can immediately open to its full extent. This wide opening through the top of the incubator permits the heated air to escape very rapidly, so that in a short time the air 50 about the capsule is cooled to normal, when the liquid in the capsule resumes its original condition and permits the lever 26 to descend. This movement lowers the pallet 22 so as to permit the weight and cord to rotate 55 the damper to its closed position again. The movement of the escapement need be very slight; and as this slight movement is effected at the end of a long lever that is lifted from a point close to its fulcrum, it is 60 evident that the bulging action of the capsule is extremely small, and that the device is highly sensitive. In fact the temperature can be regulated to a small fraction of one degree.

65 By lowering the yoke 31, which can be

done by the nuts 34 on the posts 33, the capsule and rod 29 will be lowered so as to separate the latter from the lever 26, and permit the weight of the lever to be borne by the escapement. When in this position the 70 damper will be closed, and it will require a much wider bulging of the capsule to trip the escapement. It is thus seen that the temperature at which the damper will open is easily controlled. When the nuts 34 are 75 loosened, the posts 33 and yoke 31 are forced downwardly by the springs 35 coiled about the posts. The cord is rewound upon the arbor 10 by simply rotating the escapement wheel backwardly with the finger. 80

As will be seen from the above description, I have provided a heat regulator in which a very small movement in a thermostatic device results in fully opening or closing a large passage for heated air or other gases, 85 thereby insuring a quick return to the normal temperature.

While the invention is shown as applied to an incubator, it is evident that it is adapted to a more general use, it being only 90 necessary that the capsule be contained in the fluid the temperature of which it is desired to regulate.

Having thus described my invention, what I claim as new and desire to secure by 95 Letters-Patent is:

1. The combination of a casing having an inlet and an outlet, means for supplying heating fluid through the inlet to said casing, a damper in said outlet, a shaft to which said damper is pivoted, an escapement wheel on said shaft, an escapement lever pivoted in operative relation to said wheel, a lever pivoted to said casing and having an end operatively connected with the escapement lever, a thermostat within said casing, and an adjustable member interposed between said thermostat and said lever and adapted to engage the lever near the fulcrum thereof, substantially as specified. 100

2. The combination of a casing having an inlet and an outlet, means for supplying heating fluid through the inlet to said casing, a damper in said outlet, a shaft to which the center of said damper is pivoted, an escapement wheel on said shaft, an escapement lever pivoted to coöperate with said escapement wheel, an elongated lever pivoted near one end to said casing and having its other end in engagement with said escapement lever, a thermostat within said casing, and a member connected with said thermostat and adapted to engage said lever near the fulcrum thereof substantially as specified. 115

3. The combination of a casing having an inlet and an outlet, means for supplying a heating fluid through the inlet to the casing, a rotary damper pivoted in the outlet, means tending to rotate said damper, an es- 120

capement wheel mounted on the pivot of said damper, an escapement lever coöperating with said wheel, an elongated lever pivoted near one end and having the other end connected to one of the arms of the escapement lever, a thermostat within said casing, and means connected with said thermostat and adapted to engage the lever at a point near the pivot and intermediate of the same and the escapement lever, substantially as specified.

4. The combination of a casing having an inlet in the lower portion thereof and an outlet in the upper portion thereof, means for supplying a heating fluid through said inlet, a transverse shaft extending across said outlet, a damper secured at its center to said shaft, means tending to rotate said shaft, an escapement wheel on said shaft, an escapement lever pivoted in operative relation to said wheel to control the movement thereof, a lever pivoted near one end on top of said casing and having its other end connected to said escapement lever, a thermostat within said casing, a rod connected to said thermostat and extending through said casing in proximity to the pivot and between the same and the escapement lever, and means for adjusting the position of said thermostat to vary the amount of expansion necessary to bring the outer end of said rod into contact with said lever, substantially as specified.

5. The combination of a casing having an inlet and an outlet, means for supplying heating fluid through the inlet to said casing, a damper in said outlet, a shaft to which the damper is secured at its center, means tending to rotate said shaft and damper, an escapement wheel on said shaft, said escapement wheel having a pair of teeth diametrically opposed to each other, an escapement lever pivoted in position to engage said teeth, said escapement lever having a pair of pallets

lets the distance between which is equal to half the distance between the escapement teeth, a thermostat in said casing, and means operatively connecting said thermostat and said pallet lever, substantially as specified.

6. In a device for regulating the heat in an incubator, a housing on the upper side of the incubator, said housing forming part of a passage for gases from the incubator, a rotating damper having its shaft journaled in the sides of the housing, a cord and weight tending to rotate the said damper, an escapement wheel secured to the shaft of the damper, an escapement lever supported by the housing and controlling the movements of the escapement wheel, a horizontal lever pivoted near one end and supported on the top of the incubator, said lever having its end opposite the pivot engaging with the escapement lever, a capsule containing a volatile liquid within the incubator, a yoke upon which the capsule is supported, rods attached to the ends of the yoke and extending upwardly through the top of the incubator, the upper ends of said rods being screw threaded, springs tending to force the rods and the yoke downwardly, nuts on the rods whereby the capsule may be lifted or lowered in the incubator, a stem projecting upwardly from said capsule and adapted to engage the said horizontal lever, the adjustment for the capsule being such that a variable degree of movement of the stem may be necessary before the lever will be moved to release the escapement wheel.

In testimony whereof I affix my signature in the presence of two witnesses.
